YARN CARRIER STOP CONTROL MECHANISM FOR FLAT KNITTING MACHINES

Application filed December 30, 1929. Serial No. 417,430.

This invention relates to yarn stop carrier control mechanism useful in connection with flat knitting machines such as are employed in the manufacture of full fashioned hosiery and the like.

Flat knitting machines of the type referred to, are ordinarily equipped with a number of carriers for feeding different kinds of yarn to the needles, said carriers being secured to individual longitudinally extending slide rods whereto reciprocatory motion is imparted, through friction boxes, from what is known as the friction box rod which has a fixed throw. Incidental to fashioning of the stockings, the movement of the carrier rods is variously limited by individually associated end stops on screw operated nuts of narrowing heads at opposite extremities of the machine. To permit selection as between the yarn carrier stops, the latter are pivotally mounted on the narrowing head nuts so that they can be manually swung into and out of action. This operation entails stoppage of the machine and therefore retards production, and, moreover, requires the exercise of skill on the part of high salaried attendants.

The purpose of my present invention is to overcome the drawbacks to which attention 30 has been directed through provision of means whereby the selection of the yarn carriers is accomplished entirely automatically and with the machine in operation.

A further aim of my invention is to secure 35 the foregoing desiderata with a simple mechanism in the form of an attachment capable of being readily applied to standard knitting machines without necessitating any alteration whatever in them nor interfering with their normal mode of operation.

Still other objects and attendant advantages will be manifest from the detailed description of the attached drawings, whereof Fig. I is a skeletonized partial rear elevation of a full fashioned stocking knitting machine conveniently embodying the stop control mechanism of my invention, with certain portions broken out and others shown in section to expose important details.

Fig. II is a fragmentary end elevation of

the machine viewed as indicated by the arrows II—II in Fig. I.

Fig. III is a fragmentary cross section taken as indicated by the arrows III—III in Fig. I.

Fig. IV is a detail sectional view, taken as indicated by the arrows IV—IV in Fig. II, and showing one of the yarn carrier stop levers in active position.

Fig. V is a view similar to Fig. IV with the stop lever moved to inactive position; and,

Fig. VI is a perspective view of one of the carrier rod stops modified for the purpose of my invention.

The knitting machine partly shown in the several illustrations is, generally speaking, of standard construction in that it embodies a multiplicity of longitudinally extending yarn carrier rods 10. These yarn carrier rods 10 are supported for endwise sliding movement by suitable brackets (not shown) afforded by the machine frame which is designated 11, and receive movement by virtue of connection, through friction boxes, from the friction rod (not shown) of the machine, all in a well-known manner. As usual, the machine is provided with narrowing heads at opposite ends, one such head being shown and comprehensively indicated by the numeral 12 in Figs. I and II. Each such narrowing head comprises among other parts, a lead screw 13 for the carrier rod stop nut 14, said screw being rotatable in bearings 15 which are provided by brackets 17, 18 bolted to a horizontal supporting bar 19 of the machine frame. As usual, the nut 14 is formed with spaced angularly projecting ears 20, 21 (Fig. II) that support between them a transverse axis rod 22, whereon are mounted for independent move-

ment, a series of gravity-influenced stop levers 23, in this case four, which are properly allocated to co-operate with certain of the yarn carrier rods 10, and fitted on their free ends with adjustable stop screws 24. By means of integrally formed handles 25, the stop levers 23 are swingable manually on the axis rod 22 into and out of active position relative to the co-ordinated carrier rods 10 in a manner well understood.

As hereinbefore stated, the chief aim of my present invention is to control the yarn carrier stop levers 10 of a knitting machine such as just briefly described, automatically. The mechanism which is provided for this purpose includes a shaft 26 having support in supplemental bearing arms 27, 28 bolted or otherwise fastened to the ears 20, 21 on the nut 14 of the narrowing head 12. On this shaft 26 are secured, with capacity for rotative adjustment by means of screws 29, a number of collars 30 to align with the stop levers 23. The heads of the screws 29 are adapted, when the shaft 26 is turned, to engage lugs 31 secured to the bosses of said stop levers, see Figs. IV, V and VI, more particularly. From these illustrations it will be noted that the lugs 31 are adjustably secured to the stop levers 23 by means of screws 32 which pass through longitudinal slots in the tails 31a of said lugs. In effect, the collars 30 constitute adjustable sections of a rotary drum element with circumferentially spaced radial projections—the screw heads 29—which are influential individually upon the stop levers 10 in swinging the latter into and out of action, as shown to the best advantage in Figs. IV and V. On the end of the shaft 26 is secured a spur gear 33 to mesh with a companion spur gear 34 that rotates freely on a stud projecting outward from the ear 21 of the nut 14. Rigidly fastened to the gear 34 is a miter pinion 35 which in turn meshes with a miter pinion 36 on a positionally fixed shaft 37 that extends parallel with the lead screw 13 and has journal support in outwardly reaching bearing arms 38, 39 of the brackets 17, 18. To predetermine travel of the miter pinion 36 along the shaft 37 under influence of the nut 14, its hub is circumferentially grooved as at 40 in Fig. I for engagement by a forked arm 41 rigidly secured to the ear 21 of the nut 14. Incident to sliding after the manner just explained, the pinion 36 is obliged to rotate with the shaft 37 by virtue of a spline connection 42. For intermittently rotating the shaft 37 in order to effect successive actuation of the carrier rod stop levers 23 as more fully explained later, I secure adjacent the bearing 50, a ratchet wheel 43 which is arranged to be picked by a spring influenced pawl 44 on a lever 45 free to swing on said shaft. This lever 45 is coordinated, through the medium of a downward link 46, to the longer extremity 47a of a bell crank lever 47 with fulcrum attachment at 48 on a supplemental bearing bracket 49 secured to the longitudinal channel rail 50 at the back of the machine frame. The shorter arm 47b of the bell crank lever 47 is fitted with a roller 51 to engage a sinuous face groove 52 of a rotary cam 53 secured to an auxiliary cam shaft 54 that extends longitudinally of the back of the machine where it is supported in bearings having capacity for 65 vertical as well as horizontal adjustment

relative to the machine frame 11, one of such bearings being illustrated at 55 in Fig. III. As shown in Fig. II, the groove 52 of the cam 53 has several rises 52a which are instrumental in causing rocking of the bell crank lever 47, and, through the connections previously described in effecting picking of a tooth of the ratchet wheel 43 on the shaft 37 at each actuation. It is to be understood that the parts thus far described are duplicated in connection with the narrowing head at the opposite extremity of the machine.

Any suitable means may be employed for rotating the auxiliary shaft 54 intermittently to bring about the above described operation, but it is preferred to govern its movements from the measuring chain of the machine which is partly shown at 56 in Figs. I and III. To this end the chain 56 is fitted with a series of special lugs or buttons 57 for engaging a roller 58 on an arm 59 secured to one end of a shaft 60. This shaft 60 extends crosswise of the machine and is journaled in supplemental bearings 61, 62 bolted respectively to the longitudinal channel rail 50 at the back of the machine and the angle rail 63 at the front. At its opposite end, the shaft 60 has secured to it an arm 64 which is coupled, through the medium of an upwardly extending link 65, with the laterally extending arm 66a of a pawl guard 66 free to swing on the auxiliary cam shaft 54. The segmental portion 66b of the pawl guard 66 operates to control picking of a ratchet wheel 67 secured to the auxiliary cam shaft 54, by a pawl 68 which is pivoted to the end of another arm 69 free on said cam shaft along side the pawl guard 66, see Figs. I and III. The pawl arm 69 is constantly vibrated by virtue of connection to the rod 70 of an eccentric 71 mounted on the main shaft of the machine shown at 72 in Figs. I and III.

The operation of my invention is as follows: Each time that one of the special buttons 57 on the measuring chain 56 passes beneath the roller arm 59 (Fig. I), the transverse shaft 60 is slightly rotated and movement communicated, through the arm 64 and the link 65, to the pawl guard 66. The sector 66b of the pawl guard 66 is consequently retracted to permit picking of one tooth of the ratchet wheel 67 by the pawl 68. Due to the movement thus induced in the auxiliary cam shaft 54, one of the rises 52a of the groove 52 in the rotary cam 53 is brought into line with the roller 51 on the bell crank lever 47, and motion thereby imparted, to said bell crank lever for communication, through the link 46, to the arm 45 serving the pawl 44 which is coordinated with the ratchet wheel 43 on the shaft 37. Under these circumstances, the shaft 37 is rotated through an angular extent corresponding to the pitch of the teeth of the ratchet wheel 43; and this motion is transmitted, through the bevel

gears 36, 35 and the spur gears 34, 33, to the shaft 26 on the yarn carrier stop nut 14 carrying the drum collars 30 for actuating the swingable stop levers 23.

5 By suitably adjusting the drum collars 30 on the axis 26 to variously allocate the projecting heads of the screws 29 angularly and by correspondingly arranging the buttons 57 on the measuring chain 56, any desired sequence or order of selection may obviously be predetermined for the end stop levers 23 as required incident to interchange of different yarn carriers during the knitting of the stockings on the machine in proper timed relation 10 to other events in the cycle.

20 My automatic control mechanism is thus highly advantageous not only in that it obviates mistakes common to substitution of one yarn carrier stop for another by hand as heretofore, but in that it expedites production with assurance of absolute uniformity in the articles successively knit on the machine.

Having thus described my invention, I 25 claim:

1. The combination in a flat knitting machine with a multiplicity of sliding yarn carrier rods and a series of independently pivoted end stops for the yarn carrier rods; of control mechanism for the end stops including a rotatable drum element having circumferentially spaced adjustable projections influential upon said end stops in selectively operating them, and means to intermittently 35 rotate the drum element.

2. The combination in a flat knitting machine embodying a multiplicity of sliding yarn carrier rods, and a series of independently pivoted end stops with adjustable lugs 40 for the carrier rods; of control mechanism for the end stops including a rotatable drum element having spaced circumferential projections to cooperate with the adjustable lugs on said end stops in selectively swinging the latter and means for rotating the drum element.

3. The combination in a flat knitting machine embodying a multiplicity of sliding yarn carrier rods and a series of independently pivoted end stops; of control mechanism for the end stops comprising a shaft supporting a rotatable drum element, said element including component sections capable of separate adjustment on the supporting shaft and affording a series of circumferentially spaced projections for engaging the end stops aforesaid in selectively swinging them, and means for rotating the shaft.

4. The combination in a flat knitting machine comprising a measuring chain, a multiplicity of sliding yarn carrier rods, and individually-pivoted end stops for the carrier rods; of automatic control mechanism governed by the measuring chain for selective-

ly swinging the end stops aforesaid into and out of action.

5. The combination in a flat knitting machine with a multiplicity of sliding yarn carrier rods, and independently pivoted individual end stops for the carrier rods; of automatic control mechanism, including a rotative element having circumferentially-spaced relatively-adjustable projections, governed by the measuring chain for selectively operating the end stops aforesaid. 70

6. The combination in a flat knitting machine embodying a measuring chain, a multiplicity of sliding yarn carrier rods, and a series of independently pivoted end stops 30 for the yarn carrier rods; of control mechanism for the end stops including a rotatable drum element having circumferentially spaced adjustable projections influential in selectively swinging said end stops into and 35 out of action, and means governed by the measuring chain of the machine for rotating the drum element.

7. The combination in a flat knitting machine embodying a multiplicity of sliding 40 yarn carrier rods, and narrowing mechanism comprising a screw operated nut fitted with a series of independently pivoted end stops for the yarn carrier rods; of control mechanism for the end stops including a drum element rotatably supported by the nut aforesaid and having circumferentially spaced adjustable projections influential in selectively swinging the end stops into and out of action, and means for rotating the drum element. 125

8. The combination in a flat knitting machine embodying a measuring chain, a multiplicity of sliding yarn carrier rods, and narrowing mechanism comprising a screw operated nut fitted with a series of independently pivoted end stops for the yarn carrier rods; of control mechanism for the end stops including a drum element rotatably mounted on the nut and having circumferentially spaced adjustable projections influential in 110 selectively swinging said end stops into and out of action, and means governed by the measuring chain of the machine for rotating the drum element. 125

9. The combination in a flat knitting machine embodying a multiplicity of sliding yarn carrier rods, and narrowing mechanism comprising a screw operated nut fitted with a series of independently pivoted end stops for the yarn carrier rods; of mechanism to control the yarn carrier end stops including a drum element rotatably mounted on the nut and having circumferentially spaced adjustable projections influential in selectively swinging the carrier rod end stops into and 120 out of action, a gear wheel on the drum element in mesh with a gear slidably splined on a positionally fixed shaft extending parallel with the screw for the nut aforesaid, a ratchet wheel on said shaft, and an auxiliary 130

cam shaft with a rotary cam thereon for actuating a pawl to pick the ratchet wheel.

10. The combination in a flat knitting machine embodying a measuring chain, a multiplicity of sliding yarn carrier rods, and narrowing mechanism comprising a screw operated nut fitted with a series of independently pivoted end stops for the yarn carrier rods; of mechanism to control the yarn carrier end stops including a drum element rotatably mounted on the nut aforesaid and having circumferentially spaced adjustable projections influential in selectively swinging the yarn carrier rod end stops into and out of action, a gear wheel on the drum element in mesh with a gear slidable on a positionally fixed shaft extending parallel to the screw for the nut aforesaid, a ratchet wheel on the shaft, an auxiliary cam shaft with a rotary cam thereon for actuating a pawl to pick the ratchet wheel; and means governed by the measuring chain of the machine to impart intermittent rotary movement to the auxiliary shaft.
15. 11. The combination in a flat knitting machine embodying a measuring chain, a multiplicity of sliding yarn carrier rods, and narrowing mechanism comprising a screw operated nut fitted with a series of independently pivoted end stops for the yarn carrier rods; of mechanism to control the yarn carrier end stops including a drum element rotatably mounted on the nut and having circumferentially spaced adjustable projections influential in selectively swinging the yarn carrier rod end stops into and out of action, a gear wheel on the drum element in mesh with a gear slidable on a positionally fixed shaft extending parallel to the screw for the nut aforesaid, a ratchet wheel on the shaft, an auxiliary cam shaft with a rotary cam thereon for actuating a pawl to pick the ratchet wheel, a ratchet wheel on said auxiliary shaft, another pawl constantly vibrated through an eccentric connection with the main cam shaft of the machine, a pawl guard to control the action of the last mentioned pawl, and interposed means whereby said pawl guard is governed from the measuring chain.

In testimony whereof, I have hereunto signed my name at Philadelphia, Pennsylvania, this 26th day of December, 1929.

HAROLD F. PAGET.
